United States Patent Office.

J. Q. C. SEARLE, OF TOPEKA, KANSAS.

Letters Patent No. 98,805, dated January 11, 1870.

IMPROVEMENT IN STEAM-BOILER FURNACES.

The Schedule referred to in these Letters Patent and making part of the same.

I, J. Q. C. SEARLE, of Topeka, county of Shawnee, State of Kansas, have invented an Improvement in Furnaces or Fire-Places, of which the following is a specification.

Nature and Object of the Invention.

The main feature of my invention consists of the combination, with the fire-place of a locomotive or other boiler, of a fuel-supply reservoir surrounded by a water-space, and arranged within the fire-place, and above the grate, so as to afford a continuous supply of fuel to the fire.

Another feature of my invention consists of a grate, of a peculiar form, whereby an extended fire-surface is obtained, a thorough combustion of the fuel effected, the steam-generating capacity increased, and a continuous circulation of the water insured.

My invention also consists of further improvements, described hereafter.

Description of the Accompanying Drawings.

Figure 1 is a sectional elevation of part of a locomotive-boiler, with my invention applied to the same;

Figure 2, a transverse section on the line 1-2, fig. 1; and

Figure 3 represents a modification of my invention.

General Description.

A is the outer shell of the fire-box end of a locomotive-boiler, B being the fire-box, and *a a* the usual flue-tubes, extending through the cylindrical portion of the boiler, from the plate *b* of the fire-box to the smoke-chamber.

The inner casing or lining *c* is arranged within the fire-box, so as to form the usual water-space *e*, round the fire-chamber; and above this lining, and communicating with the fire-chamber, is a reservoir, which, in the present instance, is of a conical form, and which consists of plates *f f' f'*, secured to and forming continuations of the plates of inner lining *c*, the reservoir being so arranged that there shall be a water-space on all sides of it.

A partition, *t*, may extend transversely across the reservoir, for a purpose described hereafter.

At the front end of the boiler is a feed-opening, *g*, communicating with the reservoir *c*, and below this opening is the ash-pit opening *g'*.

The grate consists, in the present instance, of a series of zigzag tubes, *h*, parallel with each other, and with the fire-box, and so bent as to form two or more V-shaped pockets, *i i*, for the fuel, the tubes extending through the lining *c*, and being slightly elevated at their rear ends, so that the water can flow freely through them.

The reservoir *c* is filled with fuel, which, passing

through the lower end of the said reservoir, is divided by the partition *t*, and distributed into the V-shaped pockets *i* of the grate, the air passing upward between the bars, and also across the pockets, and through the mass of fuel therein, to the flue-tubes *a*, thereby effecting a thorough combustion of the fuel in the pockets, without that in the reservoir becoming ignited.

Owing to the form to which the tubular grate-bars are bent, an extensive grate-surface is obtained, within a comparatively narrow limit, so that a much larger amount of fuel may be in active combustion at one time, than if the bars extended straight across the fire-box in the usual manner, while the passage of the draught across the masses of fuel in the pockets directs the heated products of combustion away from the reservoir, instead of toward it, as would be the case if the air passed merely upward through the fuel as usual.

Owing to the presence of a body of water in the spaces surrounding the reservoir, the latter is effectively prevented from becoming so heated as to coke the contents, while the passage of water through the grate-bars, prevents the latter from being burnt away or becoming warped, at the same time affording a means of maintaining the water in constant circulation, and increasing the steam-generating capacity of the boiler.

The reservoir may consist of two casings, with an intervening air-space, as shown in fig. 3, instead of being exposed directly to the action of the steam and water in the boiler; or the reservoir may only be partly surrounded with an air-chamber, thereby maintaining the reservoir and its contents in a comparatively cool state, and, at the same time, affording an opportunity of discharging small jets of air on to the ignited fuel, as shown by the arrows in fig. 3.

It will be evident that the reservoir may extend through and above the top of the outer casing of the fire-box, to any desired height.

A feeding-tube has-heretofore been arranged within a boiler, occupying a position above the fire-place, but this arrangement is objectionable, as the presence of the reservoir either diminishes the capacity of the boiler, or requires an enlargement of the latter to compensate for the room occupied by the feeding-tube.

It is also necessary to elevate the grate, that the latter may be adjacent to the mouth of the reservoir, and the proximity of the fire to the lower end of the boiler is detrimental to the strength and durability of the latter.

By my improvement, a means is afforded of forming these narrow water-spaces, which are so desirable, in order to quickly heat the water, and rapidly generate steam.

I do not claim, broadly, a fuel-reservoir, extending

downward into a fire-place, as this has heretofore been used; but

I claim—

1. The combination of a hopper, extending into the fire-place of a boiler, and a water-space surrounding the hopper, as specified.
2. The combination of a fuel-supply reservoir with a grate, constructed and arranged, substantially in the manner described.
3. A series of water-tubes, bent and arranged to form a pocket, or series of pockets, for retaining the fuel, substantially as set forth.
4. The partition *t*, arranged within the coal-supply reservoir, for the purpose specified.

5. The perforated air-chamber, intervening between the casing of the reservoir and the water or steam-space, as set forth.

6. The combination of the rake *D*, plate or platform *G*, and detachable lever *F*, substantially as described.

In testimony whereof, I have signed my name to this specification, in the presence of two subscribing witnesses.

J. Q. C. SEARLE.
